attorney

UNITED STATES PATENT OFFICE.

WALTER E. PIPER, OF SUDBURY, MASSACHUSETTS.

OVERSHOE PATTERN.

Application filed March 23, 1926. Serial No. 96,766.

My present invention is a novel and improved pattern for use in the manufacture of overshoes, and more particularly in the type of overshoes described and claimed in my copending application Ser. No. 94,295, filed March 12, 1916.

The overshoe illustrated and described in my said copending application is preferably equipped with an automatic closure or fastener of the metallic type, as shown in the original patents to Judson Nos. 504,037 and 504,038, and more recently developed by numerous modifications, of which the G. E. Prentice Patent No. 1,562,254, November 17, 1925, is typical.

As explained in said copending applications, overshoes equipped with such metallic fasteners, as heretofore made, have had such metallic fasteners applied at the front center line of the overshoe from the forepart up over the instep. The disadvantages and difficulties of so positioning the automatic fastener are fully set forth in said application, and need not be further described herein.

A principal feature of my present invention is that by the use of my novel pattern the entire upper shoe structure may be more accurately cut, fitted and made, with a smooth uncut surface along the front, over the instep, having the closure and attached metallic fastener at the side and substantially along the line of least distortion imparted to the shoe during walking. The overshoe constructed from my pattern is particularly advantageous as, in many instances, the shape of the wearer's foot forms a reverse curve over the instep, and because of this, the strain and twist imparted to an automatic closure or fastener along the lines heretofore made, caused irreparable damage and distortion of the fastener and soon rendered the same useless.

I believe that I am the first to discover the feasibility and desirability of positioning a metallic automatic fastener along the side of an overshoe, and the first, also, to have discovered a substantially non-flexing line along which such a metallic fastener can be applied in an overshoe, and I believe therefore, that the pattern I have devised for constructing this novel overshoe is also new, and I therefore claim the same broadly herein.

Referring to the drawings, illustrating a preferred embodiment of my invention;

Fig. 1 illustrates the pattern section from which the entire quarter and upper section is cut;

Fig. 2 illustrates the outer pocket or fan pattern;

Fig. 3 representing the inside pocket or fan pattern;

Fig. 4 illustrates the pattern from which the inside lining is cut;

Fig. 5 illustrating the cuff pattern; and

Fig. 6 representing the fastener stay.

As shown in the drawings, my novel pattern comprises the component parts 1, 2, 3, 4, 5 and 6. 1 is the pattern from which the quarter and upper section, complete in a single piece, is cut. In this pattern 1 is also a slot 7, representing, in the cut-out quarter, the cut or slot for insertion and securing of the cuff. In order to produce the neatest and most attractive overshoe possible, I provide a thread line 8, here illustrated as extending diagonally across the surface of the pattern 1 from the toe thereof. In positioning the pattern on the material to be cut, this thread line will be placed according to the thread or "grain" of the cloth, or along the warp thereof, so that in the finished overshoe the cloth or upper material will not present a distorted appearance, but will have the distinct line of the fabric running from the center line of the toe in a symmetrical sweeping line upwardly and spirally of the quarter. This is an important feature and one that I believe is new in my present invention.

2 designates the pattern piece from which the outside layer of the "fan" or pocket, which adjusts itself to the size of the leg of the wearer, is cut, and 3 is the pattern piece from which the inside layer of the "fan" is cut. It will be seen that the pattern piece 3 is larger than the piece 2, being wider to provide overlapping edges for cementing, etc. The pattern 3 is also provided with the flaps 9, extending below the bottom of the pattern 2, for cementing or securing to the adjacent portions of the completed overshoe. This fan or pocket is constructed inside of the overshoe, on the same side as the automatic metallic closure, viz., on the "inside" of the shoe.

The pattern 4 is adapted to be utilized in the cutting out of the inside lining of the overshoe, the one pattern sufficing for the lining for both sides of the overshoe. This pattern 4 is provided with a slit or slot 10,

which slot is intended to be utilized in one side of the lining only, viz, that side which is interrupted by the metallic fastener. This slot 10 is of particular importance in 5 this pattern, since it predetermines the positioning of the closure opening in the completed overshoe along non-distorting lines, and provides a smooth instep portion, with a closure opening substantially vertical, or 10 slightly inclined, along one side.

One pattern piece 5 provides for the cutting out of both inside and outside layers of the cuff, which cuff is intended to be inserted and secured in the slot or slit in the 15 quarter or upper section created by following the slot 7 in cutting out the upper portion.

From the pattern 6 is cut the fastener stay which is secured to the lining, and has a slot 20 11 adapted to aline with the slot 10 in the lining 4, and to the sides of which slot 11 are secured the interlocking sides of the automatic metallic closure or fastener. The fastener stay 6 will, of course, follow the 25 same inclination or angle as the slot 10 in the lining member 4.

With the metallic fastener secured to the opposite edges of the closure, corresponding to the slots 10 and 11, and substantially 30 along a slightly diagonal line from a position preferably over the arch of the foot up to a point practically midway of the forward and rearward portions of the top of the overshoe, I secure the advantages of having the 35 entire metallic fastener and the interlocking parts, when closed, in practically a non-movable or non-distorting line, during the necessary flexing of the overshoe while the wearer is walking. Furthermore I secure a 40 better, easier and smoother fitting over the instep. Thus, by the use of my novel pattern, I am enabled to produce an improved overshoe, with lasting qualities and yet embodying the advantages of a smooth front 45 portion and a metallic fastening. I believe that my novel pattern, utilized in the construction of such an advantageous and im-

proved overshoe, is novel, and the same is therefore claimed broadly herein.

My invention is further described and de- 50 fined in the form of claims as follows:

1. An overshoe pattern for use in the manufacture of overshoes provided with automatic fasteners, consisting of component parts comprising respectively a quarter, fan 55 sides, lining, cuff, and fastener stay, said quarter being provided with a thread line to predetermine the position of the thread of the upper fabric in the completed overshoe, a slot in said quarter for receiving and 60 securing the cuff, a slot in said lining to predetermine the position of the fastener on the side of the overshoe.

2. An overshoe pattern for use in the manufacture of overshoes provided with automatic fasteners, consisting of component parts comprising respectively a quarter, fan 65 sides, lining, cuff, and fastener stay, said quarter being provided with a thread line to predetermine the position of the thread of the upper fabric in the completed overshoe, a slot in said quarter for receiving and 70 securing the cuff, a slot in said lining to predetermine the position of the fastener, and a slot in the fastener stay alined with the 75 slot in the lining.

3. An overshoe pattern for use in the manufacture of overshoes provided with automatic fasteners, consisting of component parts comprising respectively a quarter, fan 80 sides, lining, cuff, and fastener stay, said quarter being provided with a thread line to predetermine the position of the thread of the upper fabric in the completed overshoe, a slot in said quarter for receiving and 85 securing the cuff, a slot in said lining to predetermine the position of the fastener, and a slot in the fastener stay alined with the 90 slot in the lining, said last two slots adapted to be in a predetermined alined position on the inner side of the overshoe.

In testimony whereof, I have signed my name to this specification.

WALTER E. PIPER.
